UNITED STATES PATENT OFFICE.

ERASTUS EDWIN WINKLEY, OF LYNN, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON SHOE-BOTTOMS.

1,242,503.

Specification of Letters Patent.

Patented Oct. 9, 1917.

Application filed November 29, 1912. Serial No. 734,095.

To all whom it may concern:

Be it known that I, ERASTUS E. WINKLEY, citizen of the United States, residing at Lynn, in the county of Essex and State of Massachusetts, have invented certain new and useful Improvements in Machines for Operating on Shoe-Bottoms; and I do hereby declare the following to be a full, clear, and exact description of the invention, such as will enable others skilled in the art to which it appertains to make and use the same.

This invention relates to machines for operating on shoes in a partial state of completion, and more particularly to tacking mechanisms for securing certain parts together.

The present invention relates to tacking mechanisms of the general character found in welt butting machines of the type illustrated in my prior Letters Patent of the United States, No. 1,029,037, dated June 18, 1912, in which there are provided devices for both butting the welt ends and for securing the butted welt ends to the insole.

One object of the present invention is to simplify and improve the type of tacking mechanism used in my prior machine to permit operation at a greater speed than that which has heretofore been practicable while at the same time performing the desired operations in a more efficient manner with less expenditure of power. Other objects of the invention are to improve the adaptability of the machine to operating on all sizes and styles of shoes without preliminary adjustment, and to simplify and improve the construction and operation of the devices for positioning and supporting the shoe for the tacking operation of whatever character it may be.

To the accomplishment of these objects and such others as may hereinafter appear, the features of the invention relate to certain devices, combinations and arrangements of parts, hereinafter described and then set forth broadly and in detail in the appended claims, possessing advantages which will be apparent to those skilled in the art.

The various features of the invention will be best understood from an inspection of the

accompanying drawings, illustrating its preferred embodiment, in which:—

Figure 1 is a front elevation of the machine, the lower portions of the supporting column and treadle rod being omitted;

Figs. 2 and 2^a, taken together, are a right side elevation;

Fig. 3 is a rear elevation of the parts illustrated in Figs. 1 and 2;

Fig. 4 is a sectional elevation with a portion of the frame broken away to show underlying parts;

Fig. 5 is a sectional elevation on the line 5—5, Fig. 4;

Fig. 6 is a sectional plan on the line 6—6, Fig. 4;

Fig. 7 is a sectional elevation on the line 7—7, Fig. 6;

Fig. 8 is a detail in plan of the welt rests in position beneath the welt on a welted insole shoe;

Fig. 9 is a detail in front elevation, partly in section, of one of the tacker mechanisms;

Fig. 10 is a sectional plan on the line 10—10, Fig. 9;

Fig. 11 is a detail in plan, looking from the rear of the machine, of the cam and associated devices for controlling the tacker mechanism's driving springs;

Fig. 12 is a detail in rear elevation, partly in section, of the parts illustrated in Fig. 11;

Fig. 13 is an additional detail in plan of the spring controlling cam;

Fig. 14 is a perspective, partly in section, of the heel portion of an unbotted welted shoe;

Fig. 15 is a detail, partly in section, showing the effect on the shoe, of the welt rests, when brought into welt supporting position;

Fig. 16 is a detail, partly in section, showing the position of the tacker mechanisms when in welt tacking position.

As the features of the present invention are illustrated in connection with their usefulness in securing the butted ends of the welt, of a welted, unsoled shoe, to the insole, it will be convenient to give a general description of the welt butting instrumentalities.

The illustrated embodiment of the inven-

tion is shown in a machine adapted to butt both ends of the welt at the same time, and there is provided, therefore, a pair of welt rests 1 and 2, and a pair of welt cutters 3 and 4. The rest 1 and cutter 3 are carried by a head 5 which is mounted at the right of the machine to swing in a horizontal plane on a vertical pin 6 (Fig. 6) carried by a horizontal plate 7 (Fig. 2) bolted to the top of a column 8 (Figs. 2 and 2^a). The rest 2 and a cutter 4 are also mounted in a head 9 which is pivotally mounted at the left of the machine on a vertical pin 10 (Fig. 6) carried by the plate 7. The heads 5 and 9 are mounted for simultaneous movement toward each other in order to position the rests beneath the loose ends of the welt at the opposite sides of a welted, unsoled shoe and for simultaneous separating movement to permit the unobstructed removal and insertion of the shoe out of and into operative position between the heads. To this end the head 5 carries a segment 11 which is engaged by a segment 12 (Fig. 2) formed on the vertical arm of a bell crank lever 13 pivoted on a horizontal pin 14 carried by a plate 15 rising from the right side of the plate 7 (see Fig. 2). The horizontal arm of the bell crank lever 13 is pivotally connected to a vertical rod 16 (Fig. 3), connected in turn to one end of a bar 17 (Figs. 1 and 2) carried upon the upper end of a vertical rod 18 which is connected at its lower end with a treadle 19 pivotally mounted on the base of the column 8. The bar 17 carries at its other end a second vertical rod 20 (Fig. 3) which is pivotally connected to the horizontal arm of a bell crank lever 21 pivoted on a plate 22 rising from the left side of the plate 7. The vertical arm of the bell crank lever 21 has formed thereon a segment 23 which meshes with a segment 24 carried on the head 9. To hold the heads 5 and 9 normally separated the treadle 19 is connected to the column 8 by a coiled spring 25 (Fig. 2^a). With this construction a depression of the treadle causes the heads 5 and 9 to close and the welt rests 1 and 2 to engage in the welt crease and thus grip and hold a shoe in position between the heads.

In order to permit the ready removal, insertion and adjustment of the cutters 3 and 4 the shank of each of the cutters is mounted in a clamp 26 (Figs. 4 and 7) formed by a split cutter block 27. The cutter block 27 is adjustably mounted in an inclined guideway 28 (Fig. 9) formed in a carrier 29. The members of the cutting block are moved to clamp the shank of the cutter, and the block is held in adjusted position on the carrier, by a clamping screw 30 having a shank which passes through a slot formed in the block 27. The screw 30 is threaded into the carrier and has a head which is held within

a recess formed for its reception in the front member of the block 27. Each of the welt rests 1 and 2 is provided with a body portion 31 (Figs. 7 and 8) dove-tailed into the heads and secured therein by a screw 32. These rests each comprise a guard 33 (Fig. 7 and 8) arranged to extend in a horizontal plane beneath the loose ends of the welt over the marginal portion of the heel seat of the shoe, and an inclined wing 34 having its lateral edge arranged to engage the stitches 75 of the inseam in the welt crease and its upper face roughened to hold the welt.

In order to butt the ends of the welt the cutters are first lowered from the position of Fig. 7 until their cutting edges engage the upper surface of that portion of the welt supported by the inclined wings 34 of the welt rests, and are then actuated rearwardly in the plane of the guards 33. This operation produces the desired bevel on the welt ends. With this construction the edge indicated at 35 (Fig. 8) at the line of juncture between the wing 34 and guard 33, acts as a blade coöperating with the cutter in shearing the waste piece from the welt.

Advantage is taken of the well defined edge 35 between the roughened wing 34 and the smooth guard 33 to aid the operative in positioning the shoe for the welt butting operation. To this end the insole of the shoe may be provided with a mark 36 (Fig. 8), at some time before the shoe is brought to the machine, to indicate the proper line of termination of the butted ends of the welt. By registering this mark with the edges 35 the proper position of the shoe relatively to the welt butting instrumentalities is insured without the use of gages and the judgment of the operative is not depended upon.

In order to lower the cutters into their operating plane the carriers for the cutters 3 and 4 are secured to pivot pins 38 and 39 (Fig. 6) journaled in lugs 40 and 41 carried respectively by horizontal slides 42 and 43. These slides are mounted to slide on the heads 5 and 9 beneath gibs 44 secured to the heads. To raise and lower the carriers 29 about their pivots 38 and 39 each of the carriers is provided at its forward end with a guideway 45 (Figs. 4 and 7) which slidably embraces a square sleeve 46 loosely mounted on a horizontal rod 47, the opposite ends of which are secured to oblong blocks 48 (Fig. 2) mounted to slide in vertical slots 49 formed in the vertical side plates 15 and 22. The sleeves 46 are held from movement longitudinally of the rod 47 by being each interposed between a boss having connected thereto a bearing plate 50 (Fig. 6) arranged to slide in a slot on the adjacent vertical plate, and a central sleeve 51 on the rod 47. The sleeve 51 is

provided with a pair of arms 52 pivoted on a floating rod 53 (Fig. 4) supported by a yoke frame 54 (see Fig. 1) which is pivoted on a horizontal rod 55 carried by the vertical plates 15 and 22. The rod 53 also loosely carries the forward ends of a pair of links 56 which are pivoted at their rear ends at the opposite sides of a yoke frame 57 (Figs. 4 and 5) pivotally mounted on a horizontal rod 58 carried by the plates 15 and 22. One 10 of the arms of the frame 57 carries a roll 59 which engages a peripheral groove 60 (Fig. 4) formed in a cam cylinder 61 on a shaft 62 journaled at its front end in a bearing 63 (Fig. 4) and at its rear end in a bearing carried by the back plate 65 (Fig. 2) rising from the plate 7. From the above description it will be seen that the welt butting cutter carriers 29 are hung, by their 20 guideways 45, from the lower arm of a toggle, the upper arm of which is formed by the yoke frame 54 and the lower arm of which is formed by the sleeve 51 and its arms 52. The floating rod 53 forms the 25 knuckle of the toggle and power is applied thereto by the cam groove 60, through the yoke frame 57 and links 56, to make and break the toggle. When the links 56 are drawn rearwardly by the cam the toggle is 30 broken, as shown in Fig. 4, the cutter carriers 29 are raised about their pivots 38 and 39, and the cutters are held above the welt rests. This is the location of the cutter carriers while the shoe is being positioned. 35 On starting the machine the cam moves the links 56 forward thus straightening the toggle and lowering the cutters to welt butting position.

After the cutters are lowered into their 40 operating plane they are actuated rearwardly to butt the welt. To this end the slides 42 and 43 are pivotally connected by means of links 66 and 67 (Fig. 6) to a central slide 68 mounted on the plate 7 beneath 45 gibs 69. The slide 68 carries a roll 70 which engages a peripheral groove 71 formed in a cam cylinder 72^a on the shaft 62. Thus after the cutters have been lowered by the straightening of the toggle and are held 50 rigidly in their lowered position by a dwell in the cam 60, the cam 71 operates through the slides 42, 43 and 68 to draw the carriers rearwardly, the carrier guideways 45 permitting such movement, and the knives 3 55 and 4 are thus drawn through the welt to sever the welt ends. Each cutter carrier is guided in its rearward movement by a rib 29^a, on the head beneath it, which is embraced by depending wings 29^b on the carrier 60 (Figs. 6, 7 and 9). This construction also insures that the carriers 29 move inward and outward with the heads 5 and 9. During this movement they slide longitudinally on the squared sleeves 46.

The foregoing features of the illustrated 65 machine, in so far as they relate to the welt butting operation, are not claimed herein as they form the subject-matter of a divisional application Serial No. 73,669, filed January 22, 1916.

The tack driving mechanism, used in the specific illustration for securing the butted ends of the welt of the insole, which forms the subject-matter of the present invention 70 will now be described.

The constructions shown in the drawings for storing, selecting and delivering tacks for the operation of the tack inserting mechanism are substantially the same as those which have heretofore been employed in the well known Rex pulling over machine. As shown the tacks are stored in a tack pot 72 which is provided with the tack lifting and separating devices of the machine referred to for delivering tacks to a pair of 80 covered raceways 73 (Fig. 1) from which the tacks are delivered to a pair of curved tubes 74 which conduct the tacks to the tack inserting devices. The tack pot is oscillated during the operation of the machine 85 by a horizontal shaft 75 (Fig. 2) which is driven by an eccentric 76 on the shaft 62. The lower end of each of the tubes 74 terminates in a flange 74^a (Figs. 2 and 9) carried on a bracket secured to the side plate. A 90 tube 77 forming a continuation of the tube 74 is pivoted at 78 on a swinging tacker frame 79. The two tacker frames 79 are arranged on opposite sides of the machine 95 (see Fig. 1) and are pivotally mounted on longitudinally arranged pivots 80 and 81 on inward projections of the plates 15 and 22 respectively. These frames are identical 100 in construction and so a detailed description of but one of them and the parts carried thereby is necessary for an understanding of the construction of both. Each of the tube portions 77 (Fig. 9) is normally held 105 in a position to deliver a tack into a vertical throat 83 formed in a nose 84 bolted to the frame 79, by a spring pressed plunger 85 mounted in a chamber formed in the nose 84. The bottom of the throat 83 is normally 110 closed to prevent the loss of the tack delivered thereto, by spring pressed fingers movably mounted on the nose 84. These fingers comprise, a slide 87 having a hooked, tack engaging end 86 mounted in ways 88, (Fig. 10) formed in the nose 84, and a slide 89 having a tack engaging end, abutting 115 against the end 86, mounted in ways 90 also formed in the nose. The slides are reversely actuated in their ways to normally close the opening in the throat by means of a coiled spring 91 which is interposed between a lateral projection 92 on the slide 87 and the bottom of a chamber 93 (Fig. 9) formed in the slide 89. The throat 83 is located in 120 125

vertical alinement with a tack driver 94 which is clamped to the lower end of a driver bar 95 mounted to reciprocate vertically in the frame 79. The upper end of the bar 95 is pivotally connected by means of a short link 96 (Figs. 1 and 2) to the horizontal arm of a modified bell crank lever 98 secured to a horizontal rod 99 journaled in a long bearing 100 (Fig. 9) formed at the upper end of the frame 79. The bearing 100 carries a coiled spring 101 one end of which is connected to the bearing and the other end of which is connected to a plate 102 rotatably mounted on the bearing. The tension of the spring 101 may be adjusted by rotating the plate 102 on the bearing 100 after which the plate may be secured to the frame 79 by a pin 103. The drivers 94 are maintained elevated against the power stored in the springs 101 by connections from a peripheral groove 104 formed in the cam cylinder 72^a. To this end the plates 15 and 22 respectively carry inwardly projecting pivoted arms 105 and 106 (Fig. 5) which are respectively provided with rolls 107 and 108 engaging the groove 104 in the cam cylinder 72^a. Each of the arms 105 and 106 is connected to the vertical arm of the bell crank lever 98 by a horizontally arranged rod 109 which passes through the yoke frame 57 (see Figs. 4 and 5) and engages the lower end of the bell crank lever. The construction is such that the axes of the pivot of the frame 79 and the rod 109 are in alinement (see Figs. 2 and 4). The ends of the two rods 109 are rounded, as at 110 (Fig. 2), and fit into cupped bearings (see Fig. 4), the tension of the driver springs holding them in place. With this construction the frames 79 may swing about their pivots without breaking the operative connection of the tack driver bar actuating levers 98, with rods 109 and therefore tacks may be driven whatever angular position the frame 79 may assume.

In order to swing the tacker frames 79 toward each other and thus move the tack throats 83 into proper tack driving position at opposite sides of the shoe, each frame carries a toothed segment 111 (Fig. 1) engaged by a toothed segment 112 formed on the end of an arm 113 secured to the front end of a horizontal rock shaft 114 (Fig. 2). The two rock shafts 114 are arranged at opposite sides of the machine and are journaled in bearings formed in the upper portions of the side plates 15 and 22. The rock shafts 114 are provided respectively at their rear ends with inwardly extending arms 115 and 116 (Fig. 3). The arm 115 is provided with a segmental slot 117 which embraces a sliding block 118 pivotally connected by a link 119 (Figs. 2 and 3) to a slide 120 mounted to slide vertically in ways formed centrally on the back plate 65. The slide 120 carries

a second link 121 which is pivoted at its upper end to a block 122 mounted to slide in a segmental slot 123 formed in the arm 116. The slide 120 also carries a roll 124 (Fig. 2) which engages a groove 125 formed in the face of a cam disk 126 on the shaft 62. Through the connections described a downward movement of the slide 120 will swing the frames 79 toward each other to place the throats 83 in tack driving position upon opposite sides of the shoe.

As the machine of the drawings is designed to operate upon shoes varying widely in width, means is provided for automatically adjusting the extent of movement of the frames 79 in accordance with the width of the particular shoe inserted in the machine in order that the tacks may be uniformly brought to a position for insertion through openings 127 (Fig. 8) formed in the welt rests, which rests, by their engagement with the shoe, measure its width. To this end the link 119 is connected by a link 128 to a vertical arm 129 secured to one end of a rock shaft 130 journaled in bearings 90 formed on a bracket 131 carried by the back plate 65. The rock shaft 130 also carries a horizontal arm 132 which is connected through a universally-jointed, adjustable link 133 to the pivotal connection between the bell crank lever 13 and the rod 16 (see Fig. 3). The link 121, as shown in Fig. 3, is similarly connected to the pivotal connection between the bell crank lever 21 and the rod 20. With this construction the blocks 118 and 122 are adjusted along the slots 117 and 123 when the operative swings the heads 5 and 9 toward each other to position the rests 3 and 4 beneath the ends of the welt and thus measure the width of the shoe being operated upon. As the downward movement of the slide 120 by the cam 125 is constant, the angular movement imparted to the rock shafts 114 by a rocking of the arms 115 and 116 is greater or less according to whether the blocks 118 and 122 are at the inner or outer ends of the slots 117 and 123. The position of the blocks, therefore, determines the extent of inward movement imparted to the tacker frames 79. When the inward movement of the rests under the influence of the treadle 19 ceases, the positions of the blocks 118 and 122 in the arms 115 and 116 are such as to so control the extent of the inward swing of the frames 79, under the influence of the cam groove 125, that the throats 83 will be located directly in line with the tack openings 127 in the welt rests whatever the width of the shoe being operated upon.

In order to drive the tacks after the throats have been positioned at the proper tacking points, one wall of the cam groove 104, which maintains the drivers 94 elevated against the tension of the springs 101, ter-

minates abruptly at a precipice 134 (Fig. 13) formed in the cam cylinder 72^a. When the rolls 108 and 107 successively reach the precipice the drivers are released to the influence of the springs 101. As the drivers 94 move downward under the influence of the springs the tubes 77 are pushed aside, swinging about their pivots 78, to permit the drivers to pass and engage the heads of the tacks. Downward movement of the tacks under the influence of the drivers wedges apart the spring pressed fingers forming the walls of the throats 83, thus permitting the tacks to pass out of the throats and into the shoe. As shown in Figs. 11, 12 and 13 each of the journals for the rolls 107 and 108 carries a lug 135 which, when the roll reaches the precipice 134, engages a lug 135^a projecting radially from the periphery of the cam cylinder and thus the roll is supported until it has cleared the edge of the precipice permitting an abrupt drop and consequently a sharp blow by the tack driver. After the rolls drop off the precipice they are immediately returned to the groove 104 by an incline 136 formed in the cam cylinder 72^a. This incline restores the power in the springs 101 and elevates the drivers for another tack driving operation, the tubes 77 swinging back into position and delivering tacks to the throats at this time.

The shaft 62 is driven during the operation of the machine from a pulley 137 (Fig. 2) through a "Horton" clutch the roll carrier of which is indicated generally at 138, 138^a being the sleeve within it being splined to the shaft 62. This clutch is controlled manually by the operative to start the machine but is automatically controlled upon the completion of one revolution of the shaft 62 to stop the machine. The roll carrier 138 is provided with the usual lug 139 which normally engages a spring pressed bunter 140 (Fig. 3) to release the shaft 62. The bunter 140 is mounted in a chamber 141 formed in an arm 142 which is pivotally mounted on a pin 143 secured to the back plate 65 so that the bunter can be withdrawn from engagement with the lug. The pin 143 also carries loosely a dog 144 arranged to engage a lug 144^a on the sleeve 138^a, facing oppositely to the lug 139, and hold the shaft in an invariable position when it is stationary to insure a uniform starting of the cycle of operations of the machine. The bunter 140 and dog 144 are withdrawn from the lugs 139 and 144^a, to permit the shaft to be driven by the driving pulley 137, by connections from a handle 145 (Fig. 2) located, in a convenient position for manipulation by the operative, at the front of the machine. To this end the arm 142 carries a pin 146 which is normally engaged by a hook 147 (Fig. 3) pivotally mounted on a slide 148 mounted to slide ver-

tically, beneath a plate 149, in a bracket 150 carried by the plate 7. The lower end of the slide 148 is connected by a short link 151 to an arm 152 (Fig. 2) projecting from a rock shaft 153 journaled in a bracket 154 depending from the plate 7. The rock shaft 153 also carries a forwardly extending rod 155 which supports the handle 145. When the operative raises the handle 145 the slide 148 is lowered which through the hook and pin connection rocks the arm 142 to remove the bunter 140 from its lug 139. To simultaneously remove the dog 144 from its lug 144^a the arm 142 is provided with a pin 156 which when the arm 141 is rocked in the manner described engages a tail 157 on the dog 144 and rocks it downwardly about the pin 142. This permits the springs of the Horton clutch to rotate the roll carrier 138 and grip the sleeve 138^a to turn the shaft 62. While the clutch is in operating position the lugs 139 and 144^a lie approximately side by side.

In order to immediately return the bunter 140 to a position where it may reengage its lug 139 and stop the rotation of the shaft 62 at the completion of a single revolution, the plate 149 carries a stop 158 which strikes a tail 159 on the hook 147 when the latter is lowered and rocks the hook 147 about its pivotal connection with the slide 148 thereby causing the hook to be disengaged from the pin 146. The operative now releases the handle 145 which has sufficient weight, through the connections described, to elevate the slide 148. As the slide 148 rises its upper end strikes the underside of the arm 142 and elevates the bunter 140 into the path of movement of its lug 139. The dog 144 is yieldingly supported on the arm 142 by means of a spring pressed plunger 160 which holds the dog in the path of movement of its lug 144^a. The hook 147 is actuated to again snap over the pin 146 by a spring pressed plunger 161 carried by the slide 148. The engagement of the lug 139 with the bunter 140 arrests the rotary movement of the roll carrier 138, the continued movement of the sleeve 138^a frees the Horton clutch rolls, thus freeing the roll carrier from the shaft 62, and also carries the lug 144^a past the end of the dog 144 so that when the movement of the sleeve is checked by the roll springs its return is prevented by the engagement of the lug 144^a with the end of the dog 144.

For convenience in delineation the machine has been illustrated with the parts all in a neutral position, that is, with the heads 5 and 9 carrying the welt rests and cutters 125 parallel to each other (see Figs. 1 and 6) and consequently the segments 11 and 24 in central position and the blocks 118 and 122 at the centers of the slots in the arms 115 and 116 respectively (see Fig. 3). It will be

clear, however, from the foregoing description, that when the machine is at rest, ready for the insertion of a shoe, the heads 5 and 9 are at an angle to each other and in their outermost positions permitted by the upward movement of the treadle rod 18, determined by the engagement of the treadle with the stop 19^a (Fig. 2^a), which will cause the blocks 118 and 122 to rest in the outer ends of the slots in the arms 115 and 116 respectively. At this time the tacker frames 79 and driver bars 95 are in the position shown in Figs. 1 and 9 with the upper ends of the tack tubes 77 beneath the lower ends 15 of the tack tubes 74, due to the slide 120 being in its upper position, as in Fig. 3. The cutters are raised as in Figs. 1 and 4 with the toggle broken.

In operating the machine illustrated in the drawings the operative inserts a welted, unsoled shoe between the heads 5 and 9 and then depresses the treadle 19 to bring the welt rests into position in the welt creases at the opposite sides of the shoe. As the heads swing in, the operative manipulates the shoe until the mark 36 on the insole, if it be marked, registers with the edges 35 on the welt rests. After the welt rests have engaged the shoe the operative may, by applying further pressure to the treadle, cause the welt rests to tighten the materials of the shoe at the welt butting points if considered desirable. As heretofore described the narrower the shoe being positioned, the greater will be the movement of the blocks 118 and 122 toward the inner ends of their slots in the arms 115 and 116, consequently the inward movement of the tacker frames 79 will be greater for a narrow shoe than for a wide one, as is necessary to bring the tacker throats into proper tacking relation to the welt ends. As soon as the shoe has been positioned properly the operative raises the handle 145 thus throwing in the "Horn-ton" clutch 138, 138^a. The first movement of the machine is the lowering of the cutters into the plane of the guards 33 of the welt rests. Then the cutters are actuated longitudinally of the shoe to butt the welt 50 the rearward movement being sufficient to carry them out of the way of the advancing welt tackers. As soon as the cutters sever the welt ends the tacker frames 79 swing toward each other and a tack is driven into each of the butted welt ends through the tack openings 127 as shown in Fig. 16. The tacker frames then separate, the tack tubes 74 and 77 are again joined, two new tacks are delivered to the throats 83, the cutters 55 are returned to the position of Fig. 7, the clutch thrown out, and the machine stopped. The operative now removes his foot from the treadle to permit the heads to separate and the shoe is removed the welt ends having been beveled and secured to the insole.

As soon as the handle 145 is released the hook 147 reengages the pin 142 and the clutch controlling mechanism is again so connected that the machine may be started by another upward movement of the handle. 70

It will be noted from the foregoing description that in driving a tack into the welt of a narrow shoe the tack drivers stand at a more acute angle to the plane of the insole than when driving a tack into a shoe of greater width. This is distinctly advantageous as it is desirable to drive the tack as nearly perpendicular to the metal heel seat of the last as possible so that the point of the tack will be properly turned so as to 75 clenched. The narrower shoes, such as women's work, have more rounded heel seats than the wider shoes for men's work. With the construction described as the greater widths of shoes are operated upon the adjustments 80 provide for driving the tacks more nearly perpendicular to the sole face thus compensating for the lessening curve of the heel seat and providing for an effective clenching of the tacks. If the tacks are not driven 85 substantially perpendicular to the surface of the heel seat beneath the welt, they will merely bend on the grain side of the insole, not securing the welt firmly in place and will be uncomfortable to the wearer of the 90 shoe.

It is sometimes desirable, owing to the particular style of shoe being operated upon, or for some other reason, to provide for a greater movement of one of the tacker 100 frames than the other. This is taken care of in the provision of the adjustable links 133 (Fig. 3) as it will be clear that through their adjustment the normal position of either of the blocks 118 and 122 can be 105 changed at will and consequently the path of movement of the tacker frames 79 under the influence of the cam 125. Provision is also made for delivering more than two tacks from the tack pot and if desired the 110 tack throats of each tacker frame may be duplicated and two, or more, tacks may be driven simultaneously into the welt ends at each side of the shoe. The word "tack" as used in this specification is inclusive of 115 any fastening device suitable for securing the welt to the insole.

It will be clear from the foregoing description that the conjoint use of all the illustrated devices and mechanisms in a single machine is unnecessary and, in fact, is sometimes undesirable as those skilled in the art will readily recognize, and it will further be recognized that some of the features of the machine, as for instance, the 120 tacking mechanism, may be used without others and for a variety of different operations on a shoe bottom with excellent results.

It will be clear to those skilled in this 130

class of machines and with the general objects of the present invention in view, that changes may be made in the details of structure, the described and illustrated embodiment thereof being intended as an exploitation of its underlying essentials, the features whereof are definitely stated in their true scope in the claims herewith.

What is claimed as new, is:—

- 10 1. A machine for operating on shoe bottoms, having, in combination, a pair of tacker mechanisms mounted to swing, one on each side of the machine, about independent axes, a pair of rock shafts, one on each side of the machine, operative connections between each rock shaft and tacker mechanism located on the same side of the machine, and a cam for rocking the shafts, substantially as described.
- 15 2. A machine for operating on shoe bottoms, having, in combination, a pair of tacker mechanisms mounted to swing, one on each side of the machine, about independent axes; a pair of rock shafts, one on each side of the machine, operative connections between each rock shaft and tacker mechanism located on the same side of the machine, a cam for rocking the shafts, and adjustable connections between the cam and rock shafts, substantially as described.
- 20 3. A machine for operating on shoe bottoms, having, in combination, a pair of tacker mechanisms mounted to swing, one on each side of the machine, about independent axes, a pair of rock shafts, one on each side of the machine, operative connections between each rock shaft and tacker mechanism located on the same side of the machine, a cam for rocking the shafts, adjustable connections between the cam and rock shafts, and means controlled by the width of the shoe being operated upon for adjusting the adjustable connections, substantially as described.
- 25 4. A machine for operating on shoe bottoms, having, in combination, two tacker mechanisms, one at each side of the shoe, movable across the shoe bottom about fixed axes, an actuator operating to swing said tackers a definite angular distance about their axes, and adjustable connections between said actuator and tackers to modify the angular extent of the movement normally imparted to the tackers by said actuator, substantially as described.
- 30 5. A machine for operating on shoe bottoms, having, in combination, two tacker mechanisms, one at each side of the shoe, mounted on fixed axes, an actuator operating to move said tackers inward across the shoe bottom a definite distance about their axes and then outward, means operable preliminarily to modify the extent of the inward movement normally imparted by said actuator, and means to operate said tackers

before they are moved outward, substantially as described.

6. A machine for operating on shoe bottoms, having, in combination, means for supporting a shoe, a pair of tacker mechanisms mounted to swing across the shoe bottom about fixed axes, mechanism for swinging the tacker mechanisms, and means for adjusting said mechanism to vary the extent of swinging movement imparted to the tacker mechanisms, substantially as described.

7. A machine for operating on shoe bottoms, having, in combination, means for supporting the shoe in a fixed position, a tacker mechanism including a driving spring all of which is mounted for swinging movement transversely across the shoe bottom about a fixed axis, and means for controlling the operation of the driving spring, substantially as described.

8. A machine for operating on shoe bottoms, having, in combination, a tacker mechanism including a driving spring all of which is mounted for swinging movement across the shoe bottom about a fixed axis, and means for controlling the operation of the driving spring including a rod having an axis coincident with the axis of the tacker mechanism, substantially as described.

9. A machine for operating on shoe bottoms, having, in combination, a tacker frame normally at one side of the shoe, means to move the frame inward variable distances to place it over the shoe bottom into position to drive a tack in the margin of shoes of varying widths, and means to predetermine the required extent of the movement of the tacker frame, substantially as described.

10. A machine for operating on shoe bottoms, having, in combination, a tacker frame normally at one side of the shoe, means to move the frame across the shoe bottom into position to drive a tack therein, constructed to impart a definite throw to the frame, and mechanism to vary the extent of the throw imparted by said means, substantially as described.

11. A machine for operating on shoe bottoms, having in combination, a tacker frame normally at one side of the shoe, means to move the frame across the shoe bottom into position to drive a tack therein, constructed to impart a definite throw to the frame, and mechanism controlled by the width of the shoe being operated upon to vary the extent of the throw imparted by said means, substantially as described.

12. A machine for operating on shoe bottoms, having in combination, a tacker frame normally at one side of the shoe, means to move the frame across the shoe bottom into position to drive a tack therein, constructed to impart a definite throw to the

frame, and adjustable connections in said means permitting the path of said throw to be varied, substantially as described.

13. A machine for operating on shoe bottoms, having in combination, a tacker frame normally at one side of the shoe, and means to impart to the frame a definite inward throw, of varying extent from a fixed starting point, to place it over the bottoms of shoes of varying widths in position to drive a tack in the margin of the shoe bottom, substantially as described.

14. A machine for operating on shoe bottoms, having in combination, two shoe engaging heads on opposite sides of the machine, means to move said heads inward to hold a shoe between them, two tacker frames at opposite sides of the machine, mechanism for moving said tacker frames inward across the shoe bottom into tacking position, and adjustable connections in said mechanisms to vary the extent of such movement controlled by the inward movement of said heads, whereby the tacker frames are invariably moved into proper tacking position over the shoe bottom whatever the width of shoe being operated upon, substantially as described.

15. A machine for operating on shoe bottoms, having in combination, two shoe engaging heads on opposite sides of the machine, two tacker frames at opposite sides of the machine, mechanism, including adjustable connections, for moving said tacker frames inward across the shoe bottom into tacking position, and means for moving said heads inward to hold a shoe between them and simultaneously adjust said adjustable connections to vary the inward movement of the tacker frames to accord with the width of shoe held by the heads, substantially as described.

16. A machine for operating on shoe bottoms, having, in combination, two reciprocating heads on the opposite sides of the machine, a pair of independently mounted tacker mechanisms mounted to swing one at each side of the machine about fixed axes, automatic mechanism for swinging the tacker mechanisms inwardly, including adjustable devices for varying the extent of their swinging movement, and a single means for reciprocating the heads and adjusting the adjustable devices, substantially as described.

17. A machine for operating on shoe bottoms, having, in combination, a reciprocating head having a device for engaging the shoe, an independently mounted tacker mechanism mounted to swing above the head about a fixed axis, a rock shaft, operative connections between the rock shaft and tacker mechanism, a cam, adjustable connections between the cam and rock shaft for varying the angular movement imparted to

the shaft by the cam, and a single means for moving the head inward and adjusting said adjustable connections, substantially as described.

18. A machine for operating on shoe bottoms, having, in combination, two heads on the opposite sides of the machine adapted to hold the shoe between them, two independently mounted tacker mechanisms, one above each head, means for moving the tacker mechanisms inward and outward across the shoe bottom toward and from the shoe, and means controlled by the position of the heads for determining the amount of the inward movement of the tacker mechanisms whereby they are invariably positioned to drive tacks in the same portion of the shoe whatever the width of the shoe being operated upon, substantially as described.

19. A machine for operating on shoe bottoms, having, in combination, a tacker frame mounted to swing toward and from the shoe on a horizontal pivot above the shoe into and out of tacking position above the shoe, said frame having a tack throat and carrying a driver bar to operate therein, and means for imparting to said frame greater or less angular movements about its pivot as the shoe to be operated on is narrow or wide, whereby the driver bar is brought to a position substantially perpendicular to the plane of the shoe bottom, whereby the tack driven through the throat is properly clenched, substantially as described.

20. A machine for operating on shoe bottoms, having, in combination, a pair of tacker frames mounted to swing toward and from each other on a pair of horizontal pivots above the shoe, each of said frames having a tack throat and carrying a driver bar to operate therein, and means for swinging said frames about their pivots through a greater arc for a narrow shoe than for a wide shoe thus increasing the angle between the driver bars as the shoe narrows in width and maintaining said bars substantially perpendicular to the plane of the shoe bottom, substantially as described.

21. A machine for operating on shoe bottoms, having, in combination, a tacker mechanism mounted for swinging movement across the shoe bottom about a fixed axis, said mechanism including a driving spring, and means for setting and releasing said spring having an actuating device operating in the axis of the tacker mechanism, substantially as described.

22. A machine for operating on shoe bottoms, having, in combination, a tack driver, driver bar and driver spring, a tacker frame carrying said parts arranged to swing about a fixed axis, a bell crank lever connected to be operated by said spring having one arm connected with said driver bar and its other arm extending opposite the axis of the tacker

frame, and means in alinement with said axis for engaging and operating said lever to reset the spring, substantially as described.

5 23. A machine for operating on shoe bottoms, having, in combination, two tacker frames, one at each side of the shoe, an actuator and connected mechanism to move said frames inward across the shoe bottom, said actuator being constructed to impart a movement of definite extent to said frames, and means operating on said connected mechanism to modify the movement normally imparted to the tacker frames by said actuator, substantially as described.

10 24. A machine for operating on shoe bottoms, having, in combination, two shoe engaging heads on opposite sides of the machine, means to move said heads inward to hold a shoe between them, two tacker frames 20 above said heads and movable inward but

without engagement with said heads, an actuator to move said frames inward, and means operating prior to the operation of said actuator to determine the extent of inward movement imparted to said frames by said actuator, substantially as described.

25 25. A machine for operating on shoe bottoms, having, in combination, a tacker frame having mounted therein a driver bar, an independently supported driving spring and mechanism connecting said spring and bar operable to place the spring under tension to drive the bar; said frame being mounted for swinging movement across the shoe bottom about a fixed axis, and means for controlling the operation of the spring, substantially as described.
